SHADE BRACKET

Arthur C. Barr, Madison, Wis.

Application August 22, 1947, Serial No. 770,007

5 Claims. (Cl. 248—267)

1

This invention pertains to mounting brackets commonly used as supports and bearings for spring actuated shade and screen rollers although it is adaptable to other purposes and uses as will be apparent.

Brackets (sometimes called "hangers") of the character in question are usually furnished in pairs or sets, each pair or set consisting of one having a circular opening or recess forming a bearing for the reception of the cylindrical pin at one end of the shade or other roller and another having a non-cylindrical (generally rectangular) slot or recess opening to one edge of the bracket for the reception of a non-circular (generally rectangular) spring winding pin at the other end of the roller, the pin cross-section conforming to the pin bearing portion of the slot so that it will be held therein against rotation while the roller rotates.

Some shade or screen roller brackets are mounted "inside" the frame, that is, directly upon the exposed faces of the pulley stiles of the window frame so that the shade or screen when unrolled will lie at or toward the sash from, the plane of the window frame trim or inside or outside siding (as the case may be) of the frame. In other arrangements the roller supporting brackets are to be mounted "outside" or upon the frame trim or siding so as to project away from the frame (as into a room) and so that the shade will unroll over the window opening in a plane, spaced inwardly (of the room) from the plane of the inner exposed trim or siding faces about the window frame. The terms "inside" and "outside" as used herein with reference to the positions of the brackets for location of a shade, screen or other roller are to be understood as referring to bracket positions on the frame pulley stiling or its equivalent and on the frame trim or siding, or its equivalent, respectively, and not as referring to the inside or outside of a building or room.

These different roller locations require different roller mounting brackets, those for the "inside" mounting generally being relatively flat for disposition against the oppositely facing sides of the frame pulley stiles where they occupy very little space and project minimum distances toward one another, and those for the "outside" mounting generally being provided with bases for disposition against the siding or trim surfaces and with standards rising from the bases thereby to space the roller engaging portions at predetermined distances outward of the frame siding or trim. It has been necessary, therefore, to

2

manufacture and stock both types of bracket sets to meet demands thereby increasing unit costs to all concerned.

The principal object of the present invention is to provide one type of bracket easily adapted to use for rollers located in either position, that is, for "inside" or "outside" (of frame) mounting, such type, of course, made in sets of two complementary brackets, one for reception of the cylindrical pin end of a roller and the other for reception of the rectangular-section pin end of the roller. The attainment of this object eliminates the necessity for separate sets or pairs of such brackets and results in decided economies from manufacture through shipment, stocking and use.

A further object is to provide a shade bracket so constructed as to reduce the fraying of the shade along its edges due to the shade cloth traveling lengthwise of the roller and thus running out the ends.

Other objects as well as the advantages and use of the invention will be understood after reading the following description and claims and after viewing the drawing in which:

Figs. 1, 2 and 3, respectively, are top plan, front elevation and side edge elevation views of a roller mounting bracket constructed in accordance with a preferred form of the invention, the bracket illustrated being that one of a pair which receives the rectangular-section pin of the roller;

Fig. 4 is a front elevation of a mounting bracket complementary to the bracket of Figs. 1, 2 and 3, the bracket in this instance being that which receives the cylindrical pin of the roller;

Fig. 5 is a view similar to Fig. 2 showing the manner in which ears 12 may be removed, if desired, when the bracket is to be used as an "outside" type;

Fig. 6 is a view of the bracket of Figs. 1, 2 and 3, showing the transformation of the bracket from an "outside" type to an "inside" type; and

Fig. 7 is an enlarged sectional view of a fragment of a bracket showing a suitable way of making the score lines.

Brackets of the type to which the invention pertains are usually made as stampings from sheet metal although they may be made by casting or molding from metal or plastic materials and the invention may be applied, with such modification as may be appropriate, to any such suitable materials and regardless of the method of manufacture. For illustrative purposes it may be assumed that the brackets disclosed herein are made of sheet steel, bronze, brass, copper or

other metal and that they are formed by stamping them from sheets or strips with suitable cutting and drawing dies.

Each bracket of each set of brackets (Figs. 2 and 4, for example) may be similar to the other bracket of the set except for the body portion which receives the cylindrical or the rectangular-section pin of the roller and which, therefore, will be formed accordingly and in the usual manner. The bracket of Figs. 1, 2 and 3 comprises a body portion 8 the central portion 9 of which is drawn or embossed away from the general plane of the sheet to provide a "bell" and which is slotted or recessed as at 11 for reception of the rectangular-section pin of a roller. This slot and its function are well known and, per se, form no part of the invention hereof. The convex side of the "bell" is disposed toward the roller end and the rectangular-section or spring winding pin is received in the slot or recess 11 and retained therein against rotation.

Extending from each of substantially opposite sides of body 8 is an integral wing portion 12 one of which may have a circular aperture 13 and the other of which may have an elongated aperture 14 therethrough for the reception of screws or nails by which the bracket may be secured to a window frame or the like, the elongated aperture serving to permit a certain amount of adjustment relative to the fastening means; also integral with the body 8 is a standard 15, and a mounting base 16, the base being disposed at right angles to the plane of the body and having a center part cut away as at 17. Apertures 18 and 19 may be provided in the standard 15 and the base 16 for screws or nails or other fastening means as will be understood.

Between each wing portion 12 and the body portion 8 and between the standard 15 and the body portion, the metal (or other material) is cut or scored, as indicated at 21 and 22 respectively, preferably to from one-third ($\frac{1}{3}$) to one-half ($\frac{1}{2}$) of its thickness or depth thereby to weaken it to permit these portions to be broken from the body by bending them back and forth relative to the body. The scoring or cutting should be sufficient to permit the several portions to be broken away from one another without serious difficulty or distortion of the body portion or other portions to be retained unaffected but should not so weaken the whole that the final type of bracket desired will fail to support its load or otherwise properly to function. Preferably the scoring is in straight lines and uninterrupted in any line but variations from these specifications may be effected. Fig. 7 illustrates one type of cut or groove forming the "score" line.

When the bracket is to be mounted against the trim of a window or door frame in an "outside" position, it will be mounted on the standard 15 with the base 16 disposed against the vertical face of the trim, nails or screws being passed through the apertures 19 to secure it in such position. Ordinarily it will be desired to have wing portions 12 remain on the bracket so mounted so that the portions 12 act to guide the shade as it rolls up on the roller and prevent the edges of the shade becoming frayed by contact with the edge of the standard 15 as frequently occurs with brackets of the prior art. However, if desired, they may be removed by breaking them off along the score lines 21 before the bracket is fastened in its destined place. Fig. 5 shows a bracket so denuded of its wings 12 and ready for installation. If, on the other hand, the bracket is to

be mounted in an "inside" position on the window or door frame, the wings 12 will be retained as the means by which the bracket is to be secured and positioned against the frame side. In such case the standard and base portions 15—16 will be broken off by bending them relative to body portion 8 on score line 22 and the resulting bracket will appear as shown in Fig. 6.

In certain special cases, as where extra rigidity is needed and the framing structure permits (such as a corner), the wings and standard may be left attached and screws or nails may be driven through apertures 13, 14, 18 and 19 to effect security; alternatively, the wings may be removed and the bracket held in place in a corner by passing securing means through holes 18 and 19 into the framing. Each of the last two mentioned use arrangements is adapted to "inside" mounting and to a partially "outside" mounting as where the body portion 8 is to project partly or wholly away from the window or door frame.

The complementary bracket of Fig. 4 is constructed after the manner of the bracket of Figs. 1 to 3, 5 and 6, and is adapted to use in a similar way. The body portion 8¹ has a central circular boss or bell 9¹ the center of the bottom of which is struck inwardly as at 11¹ to provide a circular opening the marginal bounds of which provide a bearing support for the cylindrical pin of a roller. Wings 12¹, 12¹ correspond with the wings 12, 12 and are detachable along score lines 21¹. There is also corresponding similarity between standards and bases 15¹—16¹ and 15—16, and between the several holes or apertures 13¹—14¹, 17¹, 18¹ and 19¹ and 13—14, 17, 18 and 19, respectively. Score line 22¹ corresponds to score line 22. Therefore, one pair of such complementary brackets may take the place of two pairs of brackets of the ordinary types where one pair may only be used for "inside" mounting and the other pair only for "outside" mounting. The resulting savings in material, stocking and use are very substantial.

The invention being susceptible of various modifications and changes in construction for adaptation to other designs and uses, as will be obvious to those skilled in the art, I desire to be limited only by the invention spirit and the scope of the appended claims.

I claim:

1. A shade roller bracket of the character described comprising a body portion having a roller pin receiving and supporting seat, a base portion, a standard portion joining and spacing the body and base portions, oppositely directed wing portions extending laterally outwardly from and in the plane of the body portion, and portions of lesser cross section connecting the wing and standard portions to the body portion for deliberate breakage of either from the body portion along a short line of cleavage.

2. As an article of manufacture a shade roller bracket for supporting a roller of the character described comprising a body having a portion disposed at one side of the plane of the body for supporting and positioning a roller pin, integral wing portions extending laterally outwardly from substantially opposite side edges of the body and disposed in the plane thereof, and a standard extending outwardly from another side edge of the body and integral therewith, said standard portion being disposed in the plane of the body.

3. A shade roller bracket of the character

described having a body portion formed with a roller pin receiving recess, at least one wing portion attached to and extending laterally outwardly from one edge of and in the plane of the body portion, a standard portion attached to and extending outwardly from the body portion on another edge thereof, and juncture means of reduced cross sectional area for connecting said wing portion to the body portion for deliberate breakage thereof from the body portion.

4. A sheet metal shade roller bracket of the character described comprising a body having a portion with a roller pin receiving opening therein disposed at one side of the plane of the body, a securing and positioning wing portion extending laterally outwardly from each of substantially opposite sides of said body, first portions of reduced cross sectional area integrally connecting the wing portions to the body, a standard portion extending from the body intermediate of said wing portions, said standard portion and said wing portion being disposed in a plane common with said body portion a second portion of reduced cross sectional area for integrally connecting the standard portion to the body, said first and second portions shaped to permit deliberate breakage of the respective parts from the body along a sharp line of cleavage, and a securing and positioning base attached to and extending at an angle to said standard portion at a position spaced from the body.

5. A sheet metal shade roller bracket of the character described comprising a body having a roller pin receiving opening therein, a securing and positioning wing portion extending laterally outwardly from one side of and in the plane of said body and integrally connected with the body, a standard portion extending outwardly from another side of said body and integrally connected therewith, and juncture means for connecting said portions to said body, one of said juncture means being sufficiently strong to support the body when said one portion is in a fixed position and at the same time being weakened with respect to the body and said one portion for deliberate breakage of said one portion from the body along a sharp line of cleavage between said portion and the body.
